UNITED STATES PATENT OFFICE

JAMES F. ALLISON, OF PROVIDENCE, RHODE ISLAND, ASSIGNOR TO FREEMAN-DAUGHADAY COMPANY, A CORPORATION OF MASSACHUSETTS

CLASP

Application filed September 18, 1931. Serial No. 563,535.

This application relates to a clasp for gripping the opposite edges of a collar or for engaging a tie to hold the same in position on the shirt, or for like purposes, and has for its object to provide a means which will vary the gripping pressure in response to movement of the material gripped by the means.

Another object of this invention is the provision of a friction member which will rock to assist in initial movement of the fabric between a pair of jaws, and will move to a given position to either more tightly or more loosely grip the fabric, as desired.

15 A further object of this invention is the provision of jaws that may be moved to engage the fabric with ease but initially withdrawn with greater difficulty.

20 A still further object of this invention is the provision of a rockable member which will be limited in its movement to and from certain gripping positions.

25 With these and other objects in view, the invention consists of certain novel features of construction, as will be more fully described, and particularly pointed out in the appended claims.

In the accompanying drawings:

30 Fig. 1 is a top plan view of a necktie clasp of my improved construction.

Fig. 2 is a bottom plan view thereof.

Fig. 3 is a central section showing the friction member in the position it assumes at the initial insertion of the fabric.

35 Fig. 4 is a similar view showing the position of the friction member upon completion of the insertion of the fabric.

Fig. 5 is a similar view showing the position of the friction after initial withdrawing of the fabric.

Fig. 6 is a similar view showing the further withdrawal of the fabric and the position of the friction member.

45 Fig. 7 is a sectional view of a modified form of friction member.

Fig. 8 is a top plan view of a collar holder with a friction member mounted therein of modified construction from the friction member of the previously mentioned figures.

Fig. 9 is a sectional view of the construction shown in Figure 8.

Fig. 10 is a view similar to Figure 9 with the fabric inserted therein.

Fig. 11 is a section on line 11—11 of Figure 8.

The invention which I have herein illustrated is, in its broader sense, a clasp comprising a pair of jaws for gripping any material such as a fabric or the like inserted therebetween and may be applied equally well to either a collar or a tie clasp, and I have shown the invention as applied in these two forms, although other similar uses may be apparent from the structure of the device.

I have found that it is desirable to provide a pair of gripping jaws so arranged that the insertion of the fabric will be easier than its withdrawal or one in which maximum gripping position may be assumed between two 70 positions of lesser gripping tension, and in order to accomplish this result I have mounted a friction member which will exert a minimum pressure upon the fabric between the jaws upon insertion, but will rock the member to cause a maximum or increased pressure of the member on the fabric to more securely grip the fabric between the jaws upon initial withdrawing movement, and I may either limit this rocking movement so

75 that when a maximum pressure is so obtained the member will not further move to release the pressure by rocking in the same direction or I may permit further rocking to provide easy withdrawal. The construction 85 also permits of the member to rock in a reverse direction upon initial insertion of the fabric between the jaws to lessen the pressure and permit easy insertion of the collar or tie into the device; and the following is a detailed description of the present embodiment 90 of this invention, illustrating the preferred means by which these advantageous results may be accomplished.

With reference to the drawings Figures 1 95 to 7 inclusive disclose a tie clasp which is formed of wire doubled upon itself to provide a rear jaw 10 and a front jaw 11. The rear jaw is a frame with parallel portions 12 which are brought together at 13 and 100

bent to form a loop 14 for resiliency between the jaws 10 and 11. From this resilient loop the wires extend in slightly diverging relationship to form arms 15 and 16 joined by the loop portion 17 at the free end of the jaw.

The end portions 18 and 19 of the back jaw 10 turned inwardly and bent to provide an eye in which a friction member, designated generally, 20 is pivotally mounted by means of the ends of these portions 18 and 19 extending thereto. A band 21 secures the end portions 18 and 19 together and hold the cam 20 in place. The friction member 20 is provided with an eccentrically located pivot opening 22 and shaped as best shown in section in Figures 3 to 5 inclusive to provide fabric engaging teeth 23 and 24, with a smooth surface 25 at one side and a roughened surface 26 on the other side thereof.

The fabric 27 when first inserted, as illustrated in Figure 3, engages the space 28 between the teeth 23 and 24 and rocks the member about its pivot so that the roughened surface 26 will be in engagement with the fabric, thus the fabric during the latter part of its insertion will slide along the roughened surface 26. Upon initial withdrawing of the fabric from inserted position, the friction member will be rocked about its pivot to the position illustrated in Figure 5, so that the teeth 23 and 24 will engage the fabric 27 and spring the jaw 11 the maximum distance from the jaw 10 at which position the cam or gripping member will have its maximum pressure applied to the fabric. Upon further withdrawal the friction member may be rocked to the position illustrated in Figure 6 with the smooth surface 25 in engagement with the fabric to apply less pressure on the fabric and permit easy withdrawal.

Stops are suitably provided on the friction member by means of abutments 29 and 30, as shown in Figure 6, to engage the pivotal mountings 18 and 19 and limit the movement of the friction member in its rocking so as to determine the positions it will assume with relation to the fabric. Thus it will be observed that upon insertion of the fabric the member will first be rocked about its pivot through its position of maximum pressure to the position of minimum pressure illustrated in Figure 4, along which the fabric will slide upon insertion, then upon withdrawal of the fabric slightly the position of maximum pressure will be obtained and then upon further withdrawal the friction member will be tipped to the opposite side to a position of lesser pressure to permit the fabric to be moved along the smooth surface 25 in withdrawing it from the clasp.

It is known that the width of a fore-in-hand tie is such that when its edge aligns with the edge of the shirt, the tie is to one side of the center of the shirt, and it is there-

fore desirable in positioning a tie clip to leave a sufficient distance between the bight or fold 14 of the clasp and the edge of the shirt to permit the tie to be moved into this portion to center the tie on the shirt, and by the provision of this construction I may align the edge of the tie with the edge of the shirt and push the tie clasp into its extreme position then withdraw the same slightly to the position illustrated in Figure 5 in which maximum gripping occurs, and then slide the tie outwardly until it engages the bight 14. The friction member being in engagement with the shirt is not moved by sliding the tie along the shirt and front jaw and thus the tie is centered and the friction member is located in its maximum gripping position from which it may be manually released.

In some instances it is desirable to provide a member 30, as shown in Figure 7, with its surface notched to provide abutments 31 and 32 between which a finger 33 may be positioned to engage either of these abutments to limit the movement of the cam as desired. By suitably positioning these stops, I may cause the cam to function to apply the desired maximum and minimum pressures at the different relative positions of the clasp and the fabric as is desired.

In Figures 8 to 11 inclusive, I have disclosed the adoption of this member on a collar holder, which consists of a front bar 35 and a rear bar 36 which are clamped together by a band 37 to provide oppositely disposed pairs of jaws 38 and 39. In the back jaw 39, 100 I have mounted a friction member 40 which may be folded about a cross bar 41 formed by cut-out portions 42 in the jaw 39. Upon insertion of the fabric 43 the member 40 will be rocked to the minimum gripping position as illustrated in Figure 10 and there stop by engagement of its portion 44, with the jaw 39 at the edge of the opening 42, and upon withdrawal of the fabric 43 the member 40 will be rocked to cause its portion 45 to engage the opposite edge 46 of the slot 42 and limit the movement of the member so that the maximum pressure is applied to the fabric tending to resist withdrawal from between these jaws. In this case, the member being positioned in a slot may be engaged by either side of the slot to limit its movement and thus provide the desired functioning of the device without the formation of particular stops as described in connection with Figures 1 to 7 120 inclusive.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a clasp for gripping a piece of fabric,

- 5 a pair of jaws, and means mounted in one of said jaws to engage the fabric positioned between said jaws, said means being so constructed and positioned as to be moved by the relative movement of the fabric between said jaws in one direction to exert a greater pressure on the fabric than before movement and stop means to maintain said greater pressure on the fabric although permitting frictional sliding of the fabric therealong during a continued movement of the fabric in said direction. 70
- 10 2. In a clasp for gripping a piece of fabric, a pair of jaws, and means mounted in one of said jaws to engage the fabric positioned between said jaws, said means being so constructed and positioned as to be moved by the withdrawing movement of the fabric to exert a greater pressure on the fabric than before movement, and stop means to maintain said greater pressure on the fabric although permitting frictional sliding of the fabric therealong during continued withdrawing movement of the fabric. 80
- 15 3. In a clasp for gripping a piece of fabric, a pair of jaws, and means mounted in one of said jaws to engage the fabric positioned between said jaws, said means being so constructed and positioned as to be moved by the withdrawing movement of the fabric to exert a greater pressure on the fabric, and moved to exert a lesser pressure on the fabric by an insertion of the fabric into said jaws, and stop means to selectively maintain greater or lesser pressure on the fabric although permitting frictional sliding of the fabric therealong during a continued movement of the fabric in a single direction. 85
- 20 4. In a clasp for gripping a piece of fabric, a pair of resilient jaws, and means pivotally mounted in one of said jaws to engage the opposite jaw or fabric positioned between said jaws, said means being so constructed and positioned as to be moved by movement of the fabric in one direction to exert a greater pressure on the fabric, and be moved by opposite movement of the fabric to exert a lesser pressure on the fabric, and stop means to selectively maintain greater or lesser pressure on the fabric although permitting frictional sliding of the fabric therealong during a continued movement of the fabric in a single direction. 90
- 25 5. In a clasp for gripping a piece of fabric, a pair of jaws, and a friction member pivotally mounted in one jaw with its engaging surface at different distances from its pivotal mounting, and means for limiting the movement of said member about said pivot and said member being so constructed and arranged as to provide that at one limit the point of said member furthest from said pivot is nearest the opposite jaw. 95
- 30 6. In a clasp for gripping a piece of fabric, a pair of jaws, and a friction member pivot- 100
- 35 in one jaw eccentrically with its engaging surface at different distances from its pivot, and means for limiting the pivotal movement of said member in said jaw to a swing of substantially ninety degrees, said member being so constructed and arranged that it will move from one stop to the other upon insertion or removal of a piece of fabric between said jaws. 105
- 40 7. In a clasp for gripping a piece of fabric, a pair of jaws, and a member pivoted eccentrically with respect to its engaging surface in one of said jaws, and means for limiting the pivotal movement of said member in said jaw to present either a maximum or minimum gripping position, said means being so constructed and positioned as to permit movement from minimum to maximum gripping position upon withdrawal of the fabric from between said jaws and to permit movement from maximum to minimum gripping position upon insertion of the fabric between said jaws. 110
- 45 8. In a clasp for gripping a piece of fabric, a pair of jaws, a member pivoted eccentrically with respect to its engaging surface in one of said jaws, and means for limiting the pivotal movement of said member in said jaw, said means being so constructed and positioned as to permit movement from maximum to minimum gripping position upon insertion of the fabric between said jaws and to permit reverse movement from minimum to maximum gripping position upon initial retraction of the fabric from between said jaws, followed by return to minimum gripping position. 115
- 50 9. In a clasp for gripping a piece of fabric, a pair of jaws, one of said jaws being resilient, a member pivotally mounted in one of said jaws off center with respect to its engaging surface and in engagement with the other jaw to turn when fabric is moved between said jaws, and stop means to limit the movement of the member so arranged as to stop the member in a position of maximum gripping position. 120
- 55 10. In a clasp for gripping a piece of fabric, a pair of jaws, a member pivotally mounted in one of said jaws and in engagement with the other jaw to turn when fabric is moved between said jaws, said member having abutment shoulders, and means to engage said shoulders and limit the movement of said member in both directions. 125
- 60 11. In a clasp for gripping a piece of fabric, a pair of jaws, a member pivotally mounted in one of said jaws and in engagement with the other jaw to turn when fabric is moved between said jaws, a part of one of said jaws providing a pivot extending beyond the ends of said member and portions on said member to engage the pivot and limit the movement of the cam about the pivot. 130
- 65 12. In a clasp for gripping a piece of fab-

ric, a pair of jaws, a cam pivotally mounted in one of said jaws and in engagement with the other jaw to turn when fabric is inserted between said jaws, said cam having a notch 5 to provide abutment shoulders, and a finger extending into said notch to engage said shoulders and limit the movement of said cam.

13. In a tie clasp, a pair of wire jaws, and 10 means pivotally mounted in one of said jaws to resiliently engage the other jaw, said means being so constructed and positioned as to move upon initial withdrawal of the material between said jaws to increase the pressure 15 upon the material and means to limit the movement of said means in said direction to maintain the increased pressure applied.

14. In a collar holder oppositely disposed pairs of jaws and means pivotally mounted 20 in one of the jaws of each pair to resiliently engage the other jaw, said means being so constructed and positioned as to move upon movement of the collar between said jaws in one direction to increase the pressure upon 25 said collar and means to limit the movement of said means in said direction to maintain the increased pressure applied.

15. In a tie clasp, a pair of wire jaws, and 30 means pivotally mounted in one of said jaws to resiliently engage the other jaw, said means being so constructed and positioned as to move upon movement of the material between said jaws in one direction to increase the pressure upon the material, and means to 35 limit the movement of said means in said direction to maintain the increased pressure applied, said first named means being moved to lessen the pressure upon said material upon opposite movement of the material.

40 In testimony whereof I affix my signature.
JAMES F. ALLISON.
